UNITED STATES PATENT OFFICE.

ALBERT COHN AND LOUIS H. DEBS, OF CHICAGO, ILLINOIS.

CULINARY UTENSIL.

1,308,482.

Specification of Letters Patent.

Patented July 1, 1919.

Application filed May 20, 1918. Serial No. 235,495.

To all whom it may concern:

Be it known that we, ALBERT COHN and LOUIS H. DEBS, citizens of the United States, residing at Chicago, in the county of Cook

5 and State of Illinois, have invented a new and useful Improvement in Culinary Utensils, of which the following is a specification.

Our invention relates to an improvement in the class of culinary utensils, in which a 10 plurality of cup-like receptacles are joined together to provide a single utensil for use in cooking material introduced into the cups.

The ordinary muffin-pan is an example in the class referred to; and since we have devised 15 our invention more especially for embodiment in that particular kind of culinary utensil, the description hereinafter contained is confined thereto with reference to the accompanying drawing illustrating the same.

20 A well-known form of muffin-pan comprises a flat and generally rectangular plate, usually of sheet-metal, having a plurality of series of openings formed in it; each opening containing a cup secured in place about its edge to form a permanent part of the structure. That construction is wasteful of the metal; and the primary object of the 25 present invention is to avoid such waste.

In the drawing, Figure 1 is a top plan 30 view of a muffin-pan embodying our invention in its preferred form, and Fig. 2 is a section on line 2—2, Fig. 1.

Our improved muffin-pan, which may best be formed of sheet-metal, comprises as its 35 essential features a central support provided with edge-recesses at intervals, and cups secured about their open ends in the recesses, each recess extending only part way about the cup therein, and the cups being spaced 40 from each other by tongues extending between adjacent cups, and which are formed by the recesses. These essential features may be embodied in various forms of the utensil, all of which are intended to be included 45 within our invention.

In the embodiment of our invention in the illustrated muffin-pan, the center supporting a plurality of cups is itself formed, as by stamping, as a cup 3, provided with a marginal flange having arc-shaped edge-recesses 4 at intervals and forming spacing-tongues 5. A cup 6 fits at its edge-portion, which may be beaded, for purposes of reinforcement, about its upper edge as represented at 50 Fig. 2, into each recess and is secured in place therein, as by stanching, riveting or

otherwise. It is found to be desirable to fold under, each upon itself, and thus stiffen the tongues 5 at their outer edge portions as indicated at 8.

60 The tongues 5 formed by cutting out the arc-shaped recesses extend, as will be seen, between the cups 6 and on a plane with the upper edge of said cups, and thus the cups are grouped about the binder in spaced apart 65 relation, thereby affording openings or channels between the cups whereby, when placed in the oven the heat currents are permitted to circulate around the cups and to the entire height thereof, thus expediting the baking 70 process with a resulting economy in the fuel employed to produce such baking heat.

The cups 6 thus cluster about the central cup 3, to which they are rigidly united, by the center or flange, in properly spaced relation, the whole forming a substantial structure, even when made of comparatively light sheet-metal, since by the union of the cups in the cluster with the central flange, all of these members tend to reinforce each other 80 against being bent out of shape and resultant mutilation of the utensil; and the central cup supplements that reinforcement, it being formed integral with the recessed flange about its edge.

85 It has been found in actual practice that the structure thus made up is less liable to distortion either in handling, or due to the effect of the heat, than the ordinary form of structures heretofore employed for this purpose where the binding metal entirely surrounds the cups. Thus when the structure is distorted by bending two of the cups upwardly or downwardly it is found that the remainder of the structure follows such movements and that there is no straight line of bending through the binder or center whereby repetition of such bending along such line would cause breakage along such weakened portion. The binder or center is 90 found to bend as a whole either upwardly or downwardly according to the direction in which such edge cups are bent. Moreover, the improved construction requires a comparatively small amount of sheet-metal to be 95 employed for producing it, with resultant economy, there being no waste, and involves relatively low cost of production.

We claim:

1. A culinary utensil comprising a binder placed between a series of cups and provided at its edge with a series of recesses of

an area sufficient to but partially surround the cups to be secured therein, and a series of cups fitting at a portion of their edges in said recesses and secured therein.

5 2. A culinary utensil comprising a binder placed between a series of cups and provided at its edge with a series of recesses of an area sufficient to but partially surround the cups to be secured therein, and a series 10 of cups fitting at a portion of their edges in said recesses and secured therein, the edge portions of said binder between said recesses extending between the cups and being secured thereto.

15 3. A culinary utensil comprising a binder placed between a series of cups and consisting of a cup having a circumferential binder-forming flange provided at its edge with a series of recesses of an area sufficient to but 20 partially surround the cups to be secured therein, and a series of cups fitting at a portion of their edges in said recesses and secured therein.

4. A culinary utensil comprising a binder

placed between a series of cups and consisting of a cup having a circumferential binder-forming flange provided at its edge with a series of recesses of an area sufficient to but 25 partially surround the cups to be secured therein, and a series of cups fitting at a portion 30 of their edges in said recesses and secured therein, the edge portions of said binder-forming flange between said recesses extending between the outer cups and being secured thereto.

35 5. A culinary utensil comprising a circular sheet-metal binder placed between a series of cups and forming a cup provided at intervals in its edge with arc-shaped recesses of an area sufficient to but partially 40 surround the cups to be secured therein, and cups fitting at a portion of their edges in said recesses and secured therein and forming a cluster about and united to the central cup.

ALBERT COHN.
LOUIS H. DEBS.
